METHOD FOR PRODUCING FOAM FOR FIRE EXTINGUISHING PURPOSES

Application filed April 24, 1926, Serial No. 104,368, and in Germany June 8, 1923.

My invention relates to a method of producing foam for fire extinguishing purposes.

My improved method consists in intimate mixing, by mechanical means, steam, gas or a gas mixture, such as air, with a liquid containing a foam-forming agent. This method may, for example, be carried out by allowing the liquid containing the foam generator to issue, in the form of a fine jet 10 under pressure, from a nozzle and causing it to suck in the gas or the like to be admixed with the liquid, by the suction action of this jet. Or if desired steam, gas or a gas mixture, such as compressed air, may be allowed 15 to issue through a nozzle and the jet of the gaseous medium caused to suck in the liquid containing the foam generator. This may be accomplished, for example, by a water-jet air-pump, an injector or the like.

20 Instead of directly forcing the solution of the foam generating substance, for example a saponin solution, through the water-jet air-pump, a foam generating agent may equally well be admixed with simply a jet of water 25 passed through the pump, the agent being sucked up by the action of the pump itself or being forced into it from the outside.

According to another modification, making 30 use of an injector or ejector, the apparatus may be arranged and employed to suck the liquid containing the foam generator from a tank. This tank may be open at the top so that its contents may be replenished as required during the progress of the extinguishing 35 work, in case the normal initial contents of the tank should not suffice to extinguish the fire to be dealt with.

Another modification of the method consists in bringing together in a mixing chamber, for example that of an injector, the liquid containing the foam generator and the gas or the like, both under pressure.

It will be understood that to the solution 45 of the foam generating substance, suitable substances or agents may be added which increase the durability of the solution and the viscosity of the foam and have a particularly favorable influence upon the conductivity of 50 the foam within the pipes. Alkaline admix-

tures are of particular importance in this respect.

The action of the air-pump, the injector or the like, may, if necessary, be assisted or increased by placing in front of their outlets 55 suitable baffling devices. If the foam has to be passed along a considerable distance in the course of use, for example across a tank containing a combustible liquid, a correspondingly wide or expanded foam conducting pipe, an open gutter or trough or the like, should be connected with the outlet of the mixing apparatus. Frequently it will, however, be unnecessary to conduct the foam itself across a considerable distance, inasmuch as it will generally be possible to apply the foam directly from the mixing device to the seat of the fire. 65

Suitable apparatus for carrying out the improved method is illustrated diagrammatically in the drawings affixed hereto. 70

In the drawings:

Fig. 1 is a diagram of an apparatus comprising a cylindrical container for the foam generator in the form of a powder; 75

Fig. 2 illustrates an apparatus in which the water-jet air-pump is directly connected with the water mains, and

Fig. 3 illustrates a slight modification of the apparatus illustrated in Fig. 2. 80

Like letters of reference denote similar parts throughout all the figures of the drawings.

Referring to Fig. 1 of the drawings, *h* designates, for example, a cylindrical receptacle which contains the foam generator in the form of a powder and which in known manner is so designed that in it the chemicals are dissolved by a stream of water passing through it. This receptacle is connected with the water mains by a pipe *i* and with the jet air-pump *d* by means of a pipe *k*. Air or other gaseous medium may be sucked in through a pipe *e* due to the action of the jet air-pump or may be forced in under pressure 90 by connecting the pipe *e* to any suitable source of the medium under pressure. With the outlet branch *f*, discharging the foam from the pump, there is connected, by means of a hose coupling *g* or the like a hose, pipe or 100

tube for conveying the foam to the fire. The pump could, however, equally well convey the foam directly to the seat of the fire.

Referring to Fig. 2 of the drawings, it will be seen that the jet pump *d* is directly connected with the water mains by a pipe *l*. Upon the pump is mounted a receptacle *m* which contains a foam generator, for example saponin, in the form of a powder or a concentrated solution. If desired a cock may be interposed between the receptacle and the pump. As soon as the pump is started the contents of the receptacle *m* is allowed to flow into the suction jet of the pump, if necessary under pressure which may also be derived from the water mains, through a pipe *n* the water acting under pressure on a piston or disc *o* above the agent in *m* so that the jet absorbs the foam generating agent and produces the foam generating solution to be dealt with by the pump. The apparatus shown in this figure might, in lieu of the arrangement mentioned, have the pipe *l* connected to a source of compressed air or steam or the like and have the pipe *e* connected to a source of water so that the water would be drawn in by the suction action of the gaseous medium.

The embodiment illustrated in Fig. 3 of the drawings differ from that represented in Fig. 2 in that the foam generator in the form of a powder or in solution is conveyed to the suction jet in the stream of the sucked in air or by this stream. For this purpose the receptacle *m* is made to discharge directly into the air suction pipe *e*.

In any of the forms of apparatus shown suitable chemical substances may be added to the solution of the foam generator or to the powder used, according to the purpose contemplated. In the event of an open receptacle or tank *m* being employed in conjunction with the embodiments illustrated in Figs. 2 and 3, as indicated in Figure 3 continuous operation is rendered possible without the addition of any further apparatus. In the embodiments according to Figure 1, continuous operation may be provided for, in well known manner, by disposing between the water mains and the jet air-pump two of the receptacles *a* or *h*, respectively, connected in parallel as indicated by the dotted line showing of a receptacle *h* in Figure 1.

In any of the embodiments illustrated the effect of the jet air-pump may, if necessary or desired, be supplemented or increased by placing in front of its outlet a distributing or baffling device, such as indicated at *p* in Figure 2, which serves to reduce excessively large foam bubbles.

While I have shown my invention in the preferred form, it is obvious that various modifications and changes may be made without departing from the spirit and scope of the invention, and I desire, therefore, that

only such limitations shall be placed thereon as are imposed by the prior art.

Where the terms "free gas" and "free gaseous medium" are employed in the claims, they are to be understood to refer to a medium existing in a gaseous state prior to the development of the foam as distinguished from a gas developed by chemical reaction in the course of producing the foam.

What I claim is:

1. The method of producing a fire extinguishing foam which comprises introducing into a flowing stream of water a saponaceous substance by the suction action of said stream, simultaneously introducing into said stream by the suction action a free gas in such a manner as to physically act upon said saponaceous substance to produce foam, and simultaneously adding to said stream an agent to render said foam durable.

2. The method of producing a fire extinguishing foam which comprises introducing into a flowing stream of water a saponaceous substance by the suction action of the stream, and simultaneously introducing into said stream, by the suction action thereof, air in such manner as to physically act upon said saponaceous substance to produce foam.

3. The method of producing a fire extinguishing foam which comprises introducing into a flowing stream of water a saponaceous substance by the suction action of said stream, simultaneously introducing into said stream by the suction action a free gas in such a manner as to physically act upon said saponaceous substance to produce foam, and simultaneously adding to said stream an agent to render said foam more viscous.

In testimony whereof I affix my signature.
